CONCRETE FORM

Filed March 24, 1923

Patented Jan. 19, 1926.

1,569,876

UNITED STATES PATENT OFFICE.

HAROLD ELWIN NOYES, OF CLAREMONT, NEW HAMPSHIRE.

CONCRETE FORM.

Application filed March 24, 1923. Serial No. 627,287.

To all whom it may concern:

Be it known that I, HAROLD ELWIN NOYES, a citizen of the United States, residing at Claremont, in the county of Sullivan and State of New Hampshire, have invented certain new and useful Improvements in Concrete Forms, of which the following is a full, clear, and exact specification.

My invention relates to concrete forms.

It has for its object to provide an improved concrete form and more particularly an improved removable concrete form. A further object of my invention is to provide an improved collapsible concrete form especially adapted to use as an inside form for chimneys or the like. A still further object of my invention is to provide an improved concrete form of improved, rugged and exceedingly simple construction, which comprises a small number of parts and which may be set up with facility in any desired length and removed with facility after the concrete has set, the construction at the same time being capable of being manufactured at small expense and withstanding the rough usage in service to which these devices are ordinarily subjected. These and other objects and advantages of my improved construction will, however, herein after more fully appear.

In the accompanying drawings I have shown for purposes of illustration one embodiment which my invention may assume in practice, the same therein being illustrated as applied to an inside form for a concrete chimney although it will be understood that the invention may be applied to other uses.

In these drawings,—

Fig. 1 is a side elevation of a form constructed in accordance with this embodiment of my invention and showing a plurality of elements disposed in longitudinally assembled relation, certain parts of the outer sheeting being broken away to facilitate illustration.

Fig. 2 is a vertical sectional view on line 2—2 of Fig. 1.

Fig. 3 is a transverse sectional view on line 3—3 of Fig. 2.

In this illustrative construction it will be noted that a plurality of improved expanding and collapsing means for the sheet metal form per se act on the form at different points in its length, improved means hereinafter described being provided where-

by the form may be expanded and collapsed, and thereafter bodily withdrawn, as for example from the top of a chimney.

Inasmuch as the same mechanisms for expanding and contracting the form may be utilized throughout the length of the form with either one set of mechanisms or a plurality of the same being used, depending upon the length of the opening to be provided, a description of one of these mechanisms will suffice for all. Accordingly reference is made more particularly to Fig. 3. In this figure it will be noted that the outer surface of the form comprises a plurality of usual metal sheets, herein four, 1, 2, 3, 4, disposed on end and herein in the form of a rectangle with rounded corners, the sheets 1 and 3 herein being duplicates and the sheets 2 and 4 being duplicates, while each sheet is provided with a raised portion 5 adapted to overlap its neighbor in overlapping telescopic fashion as shown.

Inasmuch as the connections for each of the sheets 1 and 3 are identical and the connections for the sheets 2 and 4 are likewise identical, a description of these connections for the sheets 1 and 2 will suffice for both sets. Referring to sheet 1, it will be noted that, like the sheet 4 (Fig. 2), it is suitably attached as by rivets 6 to a cross rib 7 of substantially L-shape having a rounded corner and provided in its ends with an internal T-shaped slot 8 which is adapted to receive the adjacent end of a rib 9 likewise of L-shape but of T-shape cross section at its ends, to which rib the plate 2 is attached as by screws 10, the construction being such that the members may be moved in and out of one another to expand or collapse the form. More particularly, it will be noted that the member 7 is connected as by suitable screws 11 to a suitable transversely disposed corner or stay block 12, the screws 11 herein extending through the back wall of the T-shaped slot as illustrated in Fig. 3, while the member 9 is similarly connected as by screws 13 to a similar corner or stay block 14, the screws in this instance, however, extending entirely through the member 9.

Moreover, it will be noted that the two stay blocks 12 and 14 are spaced from one another and that each of the same has formed therein at a point adjacent its inner edge a T-shaped slot 15 in which extend correspondingly formed T-shaped wedges on

opposite sides of a relatively perpendicular-
ly disposed wedge member 16, herein of
I-beam cross section (see Fig. 3), which is
capable of being moved in or out relative to
5 the blocks to force the same apart or con-
tract the same, the surfaces of the T-shaped
slots 15 in the blocks for this purpose being
inclined similarly to the wedge as shown in
Fig. 2. In the form of the invention illus-
19 trated, the wedge 16 is also carried on a
longitudinally extending member 17, herein
in the form of an angle iron, suitably at-
tached longitudinally and centrally of the
wedge member, as by rivets 18.

15 Here attention is also directed to the fact
that the stay blocks 12 and 14 of the sheet
sections 3, 4 are similarly connected by a
wedge 16 and that similar wedge mechanisms
19 extend between the blocks 12 and 14 of the
20 sheet sections 1 and 4 and 2 and 3, these
wedges moreover being connected to up-
standing members 20 similar to the mem-
bers 17 previously described. Moreover at-
tention is directed to the fact that the mem-
25 bers 17 and 20 extend longitudinally through
the form carrying as many wedges 16, 19 in
sets at different points and cooperating with
different sets of stay blocks and transverse
rib members as may be necessary to give the
30 desired rigidity to a form of the desired
length, and that the members 17, 20 likewise
extend beyond the end of the sheet metal
forms in such manner as to enable them to
be moved longitudinally from the end, as for
35 example, from the top of a chimney, in such
manner as to enable them to be operated as
desired to expand or cause contraction of the
form from that point.

40 In the use of my improved construction it
will be evident that a form may be provided
of any desired length depending upon the
requirement of the particular work being
done, and that one or more sets of transverse
45 members, stay blocks and wedge mechanisms
may be operated from an end of the form by
moving the wedges 16 and 19 in such manner
as to expand or contract the form. In a pre-
ferred operation, the two wedges 16 or the
50 different sets of wedges 16 are preferably
forced inward simultaneously while the two
wedges 19 or the different sets of wedges 19
are also preferably operated simultaneously.
As a result, it will be evident that the action
55 of each individual wedge will be such as to
force the adjacent blocks 12, 14 apart and
thereby expand the form as desired, while
the form due to the locking action of the
wedge surfaces, will be maintained in any
60 given expanded position depending upon the
extent to which the wedges have been driven
in. When, on the contrary, it is desired to
remove the form, i. e. after the concrete has
set, this may similarly be accomplished by
65 simply reversely operating the wedges, the
wedges 16 then preferably being pulled out

simultaneously, while the wedges 19 are also
preferably simultaneously pulled out. As a
result of pulling out the wedges, it will here
also be noted that due to the cooperating
70 wedge surfaces, herein in the form of the
T-shaped slot connection, the blocks 12, 14 of
each set will be drawn together in such man-
ner as to contract the form in the desired
fashion and thereby enable the same to be
75 removed longitudinally from the opening.
In this connection attention is also directed
to the fact that by reason of the T-shaped
wedge connections and the location of the
members 17, 20 relative to the wedges 16, 19,
80 it is impossible for the wedges to be with-
drawn longitudinally from any set of blocks
12, 14, the blocks instead being limited in
their contracting movement relative to the
wedges by contact of their inner edges with
85 the adjacent sides of the members 17, 20 so
that as those members are withdrawn they
must automatically carry with them all of
their cooperating mechanism including the
blocks, the transverse connections 7, 9 and
90 the form sheets 1, 2, 3, 4.

As a result of my improvement, it will be
observed that an exceedingly rugged con-
struction is provided, the transverse mem-
bers and the stay blocks cooperating with
the wedge mechanism to produce a very
95 rigid and strong construction requiring a
small number of wedge mechanisms for a
given length, although obviously the wedge
mechanisms may be repeated as often as may
be necessary to give the desired strength to
100 the form throughout its length. Moreover,
by reason of the wedge mechanism provided,
not only is such a rugged and rigid construc-
tion produced, but a construction is pro-
vided in which the parts may be extended
105 positively and quickly and to the desired de-
gree by the average workman, it only being
necessary for the wedges to be driven in to
given points indicated on the members 17,
20 to expand the form to various desired de-
grees, while, likewise due to the character of
110 these means, it is found possible to with-
draw the wedges and thereby collapse the
form, quickly and positively by any manual
or power means ordinarily available on a
construction job. Here attention is also di-
rected to the fact that by reason of the small
115 number and simplicity of parts and the du-
plication of many parts, the cost of manu-
facture of my improved form is very low.
These and other objects and advantages of
my improved construction will, however, be
120 clearly apparent to those skilled in the art.

While I have in this application specifi-
cally described one embodiment which my
invention may assume in practice, it will be
understood that this form of the same is
shown for purposes of illustration and that
the invention may be modified and embodied
125 in various other forms without departing

from its spirit or the scope of the appended claims.

What I claim as new and desire to secure by Letters Patent is:

5. 1. A concrete form comprising form carrying sections having form portions telescopic in intersecting directions, and separate internal wedge mechanisms for moving the same in each direction.
10. 2. A concrete form comprising a plurality of overlapping form carrying sections also having overlapping form portions, and internal wedge mechanism disposed alternately between the same.
15. 3. A concrete form comprising a plurality of telescopic form carrying sections also having overlapping form portions, and internal wedge mechanism disposed alternately between the same around a central opening.
20. 4. A concrete form comprising a plurality of telescopic form carrying sections also having overlapping form portions, and internal wedge mechanisms disposed alternately between the same, certain of said mechanisms being movable independently of the others.
25. 5. A concrete form comprising a plurality of telescopic form carrying sections also having overlapping form portions, and internal wedge mechanisms disposed alternately between the same with alternate mechanisms effecting movement in the same direction.
30. 6. A symmetrical concrete form comprising a plurality of engaging expandible and collapsible form carrying sections also having overlapping form portions, and alternately disposed internal expanding and collapsing mechanisms acting between the same.
35. 7. A symmetrical concrete form comprising a plurality of engaging expandible and collapsible form carrying sections also having overlapping form portions, and a plurality of internal collapsing and expanding mechanisms each acting on a plurality thereof.
40. 8. A concrete form comprising a plurality of form carrying sections having mutually telescoping transverse ribs and also having overlapping form portions.
45. 9. A symmetrical concrete form comprising a plurality of form carrying sections having mutually telescoping portions thereon in the shape of overlapping form portions, and expanding wedge mechanism therein disposed around a central opening in longitudinally spaced series of wedges.
50. 10. A rectangular concrete form comprising expansibly ribbed form carrying corner sections also having overlapping form portions, and internal wedge means disposed alternately between adjacent sections.
55. 11. A rectangular concrete form comprising expansibly ribbed form carrying corner sections also having overlapping form portions, and internal wedge means acting be-
- tween adjacent sections with alternate means operating to expand in different directions.
60. 12. A rectangular concrete form comprising expansibly ribbed form carrying corner sections also having overlapping form portions, and internal wedge means acting between adjacent sections with alternate means expanding in different directions and each set thereof independently operable.
65. 13. A symmetrical rectangular concrete form comprising collapsibly ribbed form carrying corner sections also having overlapping form portions, and internal collapsing means acting between adjacent sections.
70. 14. A symmetrical rectangular concrete form comprising spaced expansibly and collapsibly ribbed form carrying corner sections also having overlapping form portions, and internal expanding and collapsing means disposed alternately between adjacent sections.
75. 15. A rectangular concrete form comprising spaced expansibly transversely ribbed form carrying corner sections also having overlapping form portions, and wedge mechanisms alternately disposed between adjacent sections and within said portions.
80. 16. A rectangular concrete form comprising spaced expansibly transversely ribbed form carrying corner sections also having overlapping form portions, and wedge mechanisms alternately disposed between adjacent sections and within said portions, alternate mechanisms operating to expand in different directions.
85. 17. A rectangular concrete form comprising spaced expansibly transversely ribbed form carrying corner sections also having overlapping form portions, and wedge mechanisms alternately disposed between adjacent sections and within said portions, alternate mechanisms operating to contract in different directions and each set being independently operable.
90. 18. A rectangular concrete form comprising telescopically connected form carrying corner sections also having overlapping form portions, and internal expanding means therefor operable to effect expansions at right angles to one another.
95. 19. A rectangular concrete form comprising telescopically connected form carrying corner sections also having overlapping form portions, and internal collapsing means therefor operable to effect collapsing movements at right angles to one another.
100. 20. A rectangular concrete form comprising telescopically connected form carrying corner sections also having overlapping form portions, and internal expanding and collapsing means therefor operable at will to effect either expanding and collapsing movements in paths at right angles to one another.
105. 21. A rectangular concrete form comprising

- ing telescopically connected form carrying corner sections also having overlapping form portions, and internal expanding means therefor operable to effect expansions 5 at right angles to one another, said means being operable from an end of the form.
22. A rectangular concrete form comprising telescopically connected form carrying corner sections also having overlapping 10 form portions, and internal collapsing means therefor operable to effect collapsing movements at right angles to one another, said means being operable from an end of the form.
23. A rectangular concrete form comprising telescopically connected form carrying corner sections also having overlapping form portions, and internal expanding and collapsing means therefor operable at will 15 to effect either expanding or collapsing movements in paths at right angles to one another, said means being operable from an end of the form.
24. A rectangular concrete form comprising identic diagonally opposite form carrying corner sections mutually telescoping and also having their forms overlapping, and internal expansion varying means operable to effect movements in paths at right angles 20 to one another.
25. A rectangular concrete form comprising identic diagonally opposite form carrying corner sections mutually telescoping and also having their forms overlapping, and a plurality of identic internal expansion varying means operable to effect movements in paths at right angles to one another.
26. A rectangular concrete form comprising identic diagonally opposite form carrying corner sections mutually telescoping and also having their forms overlapping, and a plurality of identic internal expansion varying means operable to effect movements in paths at right angles to one 25 another, said means being operable from an end of the form.
27. A rectangular concrete form comprising sets of identic diagonally opposite form carrying corner sections mutually telescoping, and a plurality of identic wedge mechanisms each engaging one section of each set and operable to effect movement in paths at right angles to one another.
28. A rectangular concrete form comprising sets of identic diagonally opposite form carrying corner sections mutually telescoping, stay blocks carried by each section, and identic wedge mechanisms alternately disposed between sections and each engaging a stay block on each set of sections.
29. A rectangular concrete form comprising sets of identic diagonally opposite form carrying corner sections mutually telescoping, stay blocks carried by each section, and identic wedge mechanisms alternately dis-
- posed between sections and each engaging a stay block on each set of sections, said wedge mechanisms being operable from an end of the form.
30. A concrete form comprising a plurality of overlapping expansible form sections cooperating to produce a symmetrical form and each movable during expanding or collapsing of the latter, and separate mechanisms within said form for moving each of 75 said sections in different directions.
31. A concrete form comprising a plurality of overlapping expansible form sections cooperating to produce a symmetrical form and each movable during expanding or collapsing of the latter, telescopic transverse ribs carried by said form sections within the form, and separate mechanisms within said form for moving each of said sections in 80 different directions.
32. A concrete form comprising a plurality of overlapping expansible form sections cooperating to produce a symmetrical form and each movable during expanding or collapsing of the latter, telescopic transverse ribs carried by said form sections within the form, blocks carried in each of said sections, and separate mechanisms within said form for moving each of said blocks in 85 different directions.
33. A concrete form comprising a plurality of overlapping form sections, transverse telescopic rib members spaced longitudinally along the form sections, and expanding means operable to cause expansion of said sections and ribs or to permit contraction thereof comprising a plurality of longitudinally extending actuating members having at longitudinally spaced points thereon expanding members operatively associated 90 with said rib members.
34. A concrete form comprising a plurality of overlapping form sections, transverse telescopic rib members spaced longitudinally along the form sections, and expanding means operable to cause expansion of said sections and ribs or to permit contraction thereof comprising a plurality of longitudinally extending actuating members having at longitudinally spaced points thereon expanding members operatively associated 95 with said rib members, said expanding members being in the form of wedges and said rib members being provided with surfaces adapted to cooperate with said wedges.
35. A concrete form comprising a plurality of overlapping form sections, transverse telescopic rib members spaced longitudinally along the form sections, and expanding means operable to cause expansion of said sections and ribs or to permit contraction thereof comprising a plurality of longitudinally extending actuating members having at longitudinally spaced points thereon expanding members operatively associated 100 with said rib members.

- 130

with said rib members, said expanding members being in the form of wedges and said rib members being provided with surfaces adapted to cooperate with said wedges and to interlock therewith to permit longitudinal withdrawal of the whole mechanism.

36. A concrete form comprising a plurality of overlapping expansible form sections cooperating to produce a symmetrical form and each movable during expanding or collapsing of the latter, telescopic transverse ribs carried by said form sections within the form, stay blocks carried by each of said sections, and wedge mechanisms acting between adjacent stay blocks of different sections for moving the latter.

37. A concrete form comprising a plurality of overlapping expansible form sections cooperating to produce a symmetrical form and each movable during expanding or collapsing of the latter, telescopic transverse ribs carried by said form sections within the form, stay blocks carried by each of said sections, and wedge mechanisms acting be-

tween adjacent stay blocks of different sections for moving the latter, said wedge mechanisms each having a portion received in a retaining slot in a plurality of stay blocks.

38. A concrete form comprising a plurality of overlapping expansible form sections cooperating to produce a symmetrical form and each movable during expanding or collapsing of the latter, telescopic transverse ribs carried by said form sections within the form, stay blocks carried by each of said sections, and wedge mechanisms acting between adjacent stay blocks of different sections for moving the latter, said wedge mechanisms each having a portion received in a retaining slot in a plurality of stay blocks and certain of said stay blocks being attached to certain of said ribs while others of said stay blocks are attached to both said ribs and form sections.

In testimony whereof I affix my signature.

HAROLD ELWIN NOYES.
